(57) **CLAIM**

The ornamental design for a display screen portion with graphical user interface, as shown and described.

DESCRIPTION

The sole drawing FIGURE is a front view of a display screen portion with graphical user interface showing my new design. The outermost broken line illustrates the border of the display screen portion and forms no part of the claimed design. The broken line showing of some of the text and numbers illustrates portions of the graphical user interface that form no part of the claimed design.
